UNITED STATES PATENT OFFICE.

MARY SHERWOOD, OF BALTIMORE, MARYLAND.

DESIGN FOR A SCHOOL-DESK BODY.

SPECIFICATION forming part of Design No. 27,403, dated July 20, 1897.

Application filed June 14, 1897. Serial No. 640,779. Term of patent 14 years.

To all whom it may concern:

Be it known that I, MARY SHERWOOD, a citizen of the United States, residing at Baltimore, in the State of Maryland, have invented or produced a new and original Design 5 for School-Desk Bodies, of which the following is a specification.

The object of this design is to provide a novel school-desk body which is handsome, 10 ornamental, presents a characteristic, distinguishing, and symmetrical appearance to the eye, and possesses a peculiar and desirable configuration.

The leading feature of the design is a school- 15 desk having an inclined top, end panels with beveled or inclined front edges, a beveled or inclined panel portion across the front below the front edge of the top, and an underlying chamber formed by vertical and horizontal 20 portions located between the end panels.

The invention is illustrated by the accompanying drawings, in which—

Figure 1 is a perspective view of the school- 25 desk body, looking at the top thereof. Fig. 2 is a perspective view looking at the bottom of the same; and Fig. 3 is a sectional view taken through the body from front to rear to more clearly illustrate the configuration, form, or shape.

In the accompanying drawings, illustrating 30 my design, the numerals 1 indicate the end panels; 2, the inclined back panel; 3, the depressed bottom panel, and 4 the inclined top. The end panels 1 are formed at their

front edges with bevels or inclines 5 and 6, 35 arranged at different angles of inclination, and the beveled or inclined panel portions 7 and 8 extend across the front portion of the desk-body below the front edge of the inclined top. The beveled or inclined panel 40 portions 7 and 8 are at different angles of inclination, corresponding approximately to the beveled or inclined edges 5 and 6 of the end panels 1. The bottom of the desk-body contains an underlying chamber formed by the 45 vertical wall or portion 9 and the horizontal wall or portion 10, the latter containing a groove 12.

The general contour across the front of the desk-body produced by the duplex bevel 7 8, 50 in connection with the underlying chamber and the duplex beveled front edges of the end panels, produce a school-desk body which is handsome and ornamental and presents a characteristic, distinguishing, and symmet- 55 rical appearance, while it possesses a peculiar and desirable configuration.

What I claim is—

The design for a school-desk body, substantially as described and shown. 60

In testimony whereof I have hereunto set my hand in presence of two subscribing witnesses.

MARY SHERWOOD.
